US00D922350S

(12) **United States Design Patent** (10) **Patent No.:** **US D922,350 S**
Pedersen (45) **Date of Patent:** **** Jun. 15, 2021**

(54) **HEADSET FOR TELEPHONE AND COMMUNICATION EQUIPMENT**

(71) Applicant: **GN AUDIO A/S**, Ballerup (DK)

(72) Inventor: **Rasmus Trudslev Pedersen**, Ballerup (DK)

(73) Assignee: **GN AUDIO A/S**, Ballerup (DK)

(**) Term: **15 Years**

(21) Appl. No.: **29/732,356**

(22) Filed: **Apr. 23, 2020**

Related U.S. Application Data

(62) Division of application No. 29/670,994, filed on Nov. 21, 2018, now Pat. No. Des. 898,711.

(57) **CLAIM**

The ornamental design for a headset for telephone and communication equipment, as shown and described.

DESCRIPTION

FIG. 1 is a front view of a headset for telephone and communication equipment showing the new design;

FIG. 2 is bottom plan view of FIG. 1 thereof.

FIG. 3 is a top plan view of FIG. 1 thereof; the broken lines on the earpiece cushions represent the bounds of the claimed design;

FIG. 4 is a right side plan view of FIG. 1 thereof.

FIG. 5 is a left side plan view of FIG. 1 thereof.

FIG. 6 is a rear plan view of FIG. 1 thereof; and,

FIG. 7 is a top perspective view of FIG. 1; the broken lines on the earpiece cushions represent the bounds of the claimed design.

The features shown in broken lines depict environmental subject matter only and form no part of the claimed design.

1 Claim, 7 Drawing Sheets
